UNITED STATES PATENT OFFICE.

JAMES D. MUDGE, OF SEATTLE, WASHINGTON; NINA S. MUDGE ADMINISTRATRIX OF
SAID JAMES D. MUDGE, DECEASED.

TURBINE OR CENTRIFUGAL VACUUM PUMP DEVICE.

Application filed October 13, 1919. Serial No. 330,356.

To all whom it may concern:

Be it known that I, JAMES D. MUDGE, a citizen of the United States, residing at Seattle, in the county of King and State of Washington, have invented a certain new and useful Turbine or Centrifugal Vacuum Pump Device, of which the following is a specification.

My invention relates to the art of turbine or centrifugal vacuum pumps, and more particularly pertains to the automatically maintaining of the constant seal for the suction openings in the runners of said pump.

My invention will be described for purposes of illustration as applied in a vacuum heating system, but it is not to be limited in its scope to any such special application. In devices as heretofore designed for said purposes objection obtains in that said pumps become choked on account of the lack of flexibility or range of operation, or said pumps are defective in not having a sufficient supply of liquid at all times present to properly seal the suction openings. These objections pertain especially to centrifugal pumps used in said connection. In the case of reciprocal pumps serious objection obtains to the great vibration and noise developed therefrom and these features are particularly to be avoided in heating systems for buildings or dwellings. Such vacuum pumps used in connection with heating systems must be capable at times of discharging a quantity of water relatively large as compared to the normal discharge, which wide range of discharge is made imperative at times when a large condensation of steam takes place throughout the heating system. It is essential that the runner openings of the centrifugal pump be sealed with a liquid at all times to enable said pump to operate.

The object of my invention is to provide a turbine or centrifugal vacuum pump with an automatically operating liquid seal for the suction openings in the runners of said pump, and to provide such a pump which will have if occasion may require, a large pumping capacity whereby choking is avoided. A further primary object of my invention is to provide a vacuum pump which will be noiseless in its operation, free from vibration, and very economical as respects its cost of manufacture.

The above mentioned general objects of my invention, together with others inherent in the same, are obtained by the mechanism illustrated in the following drawings, the same being merely a preferred exemplary form of embodiment of my invention, throughout which drawings like reference numerals indicate like parts:

Figure 1, is a view in vertical section.

Fig. 2, is a view in section on line 2, 2 of Fig. 1.

A centrifugal turbine pump 3 has a discharge pipe 4, in the top of which discharge pipe is a check valve 5, said discharge pipe and valve being surrounded by the discharge chamber 6, having a non-condensable vapor or gas relief valve 7 near its top, which valve is float operated. A receiving tank 8 is connected to said discharge chamber by means of the connecting pipe 9 having the check valve 10, said connecting pipe opening in the receiving tank at 11. An outlet pipe 12, the inlet of which is preferably positioned above the floor of the receiving tank, is provided for said tank and may communicate either with a sewer or with a boiler feed line, a pump 13 being connected to said discharge or outlet pipe to act upon the liquid in said pipe 12. A valve 14 in said discharge or outlet pipe 12 serves to maintain the reduced pressure condition above the liquid in the receiving tank 8. A second outlet pipe 15 extends from said receiving tank 8 to the pump 3. Said second outlet pipe 15 is preferably provided with a reduced outlet portion 16 and said outlet portion is preferably disposed within a return pipe 17, on the same, or near the same level with the floor of the receiving tank. A check valve 18 is provided within said second outlet pipe 15. Pipe 19 establishes communication between the return or inlet pipe 17 and the receiving tank 8.

The operation of my device is as follows: Gases, liquids and non-condensable vapors enter the device thru the return pipe 17 that enters the pump 3, which in turn discharges the same thru the discharge pipe 4, forcing open the check valve 5 and causing said liquids, gases, and non-condensable vapors to accumulate within the discharge chamber 6 until such a time as the pressure of the liquid becomes so great that it forces open the spring or weight operated

check valve 10 causing the liquids to flow into the receiving tank 8. The air, non-condensable vapors and gases, escape from the discharge chamber 6 when the liquids 5 fill the discharge chamber 8 to such a level that the float relief valve is unseated by said liquids.

As said pump 3 operates, it produces a 10 partial vacuum in the return or inlet pipe 17, thereby aiding the force of gravity to cause all liquids contained therein to descend and said liquids thereby normally function to seal the suction openings in the runners of the vacuum pump 3. However when the 15 level of the liquids in the return pipe 17 falls below the level of the liquids in the receiving tank 8, the liquids in the receiving tank are caused to flow thru the second outlet pipe 15 to maintain the supply of liquid as a seal 20 for pump 3, thereby the liquids in the receiving tank constitute a reserve supply to function as a seal for the pump. Whenever the supply by condensation is inadequate for such purposes, a check valve 18 manifestly 25 prevents the liquid from reaching the receiving tank 8 by means of pipe 15. Connecting pipe 19 maintains the same air pressure or degree of vacuum in the receiving tank as obtains in the return or inlet pipe 17, so that 30 the liquid contained within the receiving tank is free to seek its level within said pipe 17 so far as the pressures obtaining in said pipe 17 and the said receiving tank 8 are concerned.

35 The function of pump 13 is to pump the liquid from the outlet or discharge pipe 12. This pumping being obviously necessary in view of the fact that the pressure on the liquid at the end of the outlet pipe 12 is at 40 least equal to that of the atmosphere, while the pressure above the liquid in the receiving tank 8 is very low, being a partial vacuum equal to that in the return pipe 17. Check valve 14 serves to maintain the reduced pressure condition in the receiving 45 tank 8. Pipe 20 serves to draw off any air that may accumulate in the pipe 9.

Obviously changes may be made in the 50 forms, dimensions, and arrangement of the parts of my invention without departing from the principle thereof, the above setting forth only a preferred form of embodiment.

I claim:

1. A device of the class described embodying an inlet or return pipe, a vacuum pump 55 to pump fluids and liquids out of said return pipe, a discharge pipe for said pump, a check valve in said discharge pipe, a discharge chamber enclosing the outlet of said 60 discharge pipe, a vapor or gas relief valve for said discharge chamber, a receiving tank, a connecting pipe between said discharge chamber and said receiving tank, a check valve in said connecting pipe, an outlet pipe 65 for said receiving tank, a second pump to

act upon the liquids in said outlet pipe, a check valve in the discharge outlet of said last named pump, a second outlet pipe for said receiving tank connecting said receiving tank and said first named pump, and a pressure adjusting pipe connecting said inlet or return pipe and said receiving tank. 70

2. A device of the class described embodying an inlet or return pipe, a vacuum pump 75 to pump fluids and liquids out of said return pipe, a discharge pipe for said pump, a check valve in said discharge pipe, a discharge chamber enclosing the outlet of said discharge pipe, a vapor or gas relief valve for said discharge chamber, a receiving tank, a connecting pipe between said discharge chamber and said receiving tank, a pressure adjusting valve in said connecting pipe disposed to operate at a predetermined pressure, an outlet pipe for said receiving tank, 80 said outlet pipe extending for some distance above the floor of said receiving tank, a second pump to act upon the liquids in said outlet pipe, a check valve in the discharge outlet of said last named pump, a second outlet pipe connecting said receiving tank and said first named pump, a check valve disposed in said second outlet pipe, 85 said second outlet pipe extending within said return pipe, and a pressure adjusting pipe connecting said return pipe and said receiving tank. 90

3. A device of the class described embodying an inlet or return pipe, a vacuum pump 100 to pump fluids and liquids out of said return pipe, a discharge pipe for said pump, a check valve in said discharge pipe, a discharge chamber enclosing the outlet of said discharge pipe, a vapor or gas relief valve for said discharge chamber, a receiving tank, 105 a connecting pipe between said discharge chamber and said receiving tank, a pressure adjusting valve in said connecting pipe disposed to operate at a predetermined pressure, an outlet pipe for said receiving tank, 110 said outlet pipe extending for some distance above the floor of said receiving tank, a second pump to act upon the liquids in said outlet pipe, a second valve in the discharge outlet of said last named pump, a second outlet pipe connecting said receiving tank and said first named pump, a check valve disposed in said second outlet pipe, 115 said second outlet pipe extending within said return pipe, a pressure adjusting pipe connecting said return pipe and said receiving tank, and a pipe forming a communicating passageway between the said pressure adjusting pipe and the connecting pipe between said discharge chamber and said receiving tank. 120

In witness whereof, I hereunto subscribe my name this 6th day of Oct. A. D., 1919.

JAMES D. MUDGE.
